US0D1088913S

(12) **United States Design Patent** (10) Patent No.: **US D1,088,913 S**
(45) Date of Patent: ** Aug. 19, 2025

(54) **COMBINED CONTROL UNIT AND DISPLAY INSTRUMENT FOR LEVEL SENSORS**

(71) Applicant: **VEGA GRIESHABER KG**, Wolfach (DE)

(72) Inventors: **Fabian Witt**, Hofstetten (DE); **Ralf Schaetzle**, Schiltach (DE)

(73) Assignee: **VEGA Grieshaber KG**, Wolfach (DE)

(**) Term: **15 Years**

(21) Appl. No.: **29/882,275**

(22) Filed: **Jan. 12, 2023**

Related U.S. Application Data

(62) Division of application No. 35/512,546, filed on Mar. 17, 2021 (U.S. filing date under 35 U.S.C. 384), and having an international filing date of Mar. 17, 2021, now Pat. No. Des. 1,028,751.

(57) **CLAIM**

The ornamental design for a combined control unit and display instrument for level sensors as shown and described.

DESCRIPTION

FIG. 1 is a perspective view of a combined control unit and display instrument for level sensors showing the new design;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines shown in the drawings depicts portions of the combined control unit and display instrument for level sensors that form no part of the claimed design.

1 Claim, 7 Drawing Sheets
